(57) **CLAIM**

The ornamental design for a wrapping bag, as shown and described.

DESCRIPTION

1. Wrapping bag

1.1: Front

1.2: Back

1.3: Right

1.4: Left

1.5: Bottom

Design: the upper portion of the front side film is folded inside of the bag; the wrapping bag of the design has additional thickness on the upper sides thereof as a result of its folding; design: the wrapping bag is made of transparent plastic; the portions indicated by dotted lines are disclaimed.

1 Claim, 5 Drawing Sheets(56)
